(57) **CLAIM**

The ornamental design for a four-way shuttle, as shown and described.

DESCRIPTION

FIG. 1 is a front and top perspective view of a four-way shuttle showing our new design.

FIG. 2 is a front view thereof.

FIG. 3 is a rear view thereof.

FIG. 4 is a left side view thereof.

FIG. 5 is a right side view thereof; and,

FIG. 6 is a top view thereof.

The broken lines in the drawings depict portions of the four-way shuttle which form no part of the claimed design.
